(57) **CLAIM**

The ornamental design for a medallion with illuminating perimeter, as shown and described.

DESCRIPTION

FIG. 1 is a front view of a medallion with illuminating perimeter showing our new design, wherein the medallion's illuminating perimeter is in an illuminating state; FIG. 2 is an perspective view of the medallion thereof; FIG. 3 is a back view of the medallion thereof; FIG. 4 is a right side view of the medallion thereof; FIG. 5 is a left side view of the medallion thereof; FIG. 6 is a top view of the medallion thereof; FIG. 7 is a bottom view of the medallion thereof; FIG. 8 is a front view of a medallion with illuminating perimeter, wherein the medallion's illuminating perimeter is not illuminated;

FIG. 9 is an perspective view of the medallion thereof;

FIG. 10 is a back view of the medallion thereof;

FIG. 11 is a right side view of the medallion thereof;

FIG. 12 is a left side view of the medallion thereof;

FIG. 13 is a top view of the medallion thereof; and,

FIG. 14 is a bottom view of the medallion thereof.

All broken lines are directed to environment and are for illustrative purposes only. None of the broken lines form any part of the claimed design. The radiating broken lines seen in FIGS. 1-7 indicate illumination. The dark shading in FIGS. 8-14 compared to the same region shown unshaded in FIGS. 1-7 indicates a contrast in appearance between unlit and lit regions, and does not depict any particular color, texture, or material.
